UNITED STATES PATENT OFFICE.

GEORGE BIGNELL, OF CHEYENNE, WYOMING.

DESIGN FOR A BADGE.

SPECIFICATION forming part of Design No. 21,251, dated December 22, 1891.

Application filed November 2, 1891. Serial No. 410,695. Term of patent 3½ years.

To all whom it may concern:

Be it known that I, GEORGE BIGNELL, a citizen of the United States, residing in Cheyenne, in the county of Laramie, State of Wyoming,
5 have invented and produced a new and original Design for a Badge, of which the following is a specification, reference being had to the accompanying drawing, which exhibits a
10 plan or face view of the badge.

The design is political in character, and

consists of the shield *a*, having an irregular contour, and the United States flag or banner *b*, mounted on the face thereof, as shown.

What I claim is—

The design for a badge, comprising the 15 shield and the superposed banner, as shown.

GEORGE BIGNELL.
